UNITED STATES PATENT OFFICE

99,243

DESIGN FOR A HANDLE ADAPTED FOR A STOVE OR SIMILAR ARTICLE

Alexis V. Lapteff, Detroit, Mich., assignor to Briggs Manufacturing Company, Detroit, Mich., a corporation of Michigan

Application July 11, 1935, Serial No. 57,594

Term of patent 14 years

To all whom it may concern:

Be it known that I, Alexis V. Lapteff, a citizen of Russia, residing at Detroit, county of Wayne, State of Michigan, have invented a new, original, and ornamental Design for a Handle Adapted for a Stove or Similar Article, of which the following is a specification, reference being had therein to the accompanying drawing, forming a part thereof, in which

Fig. 1 is a top plan view of the handle; and
Fig. 2 is a side elevation thereof.

I claim:

The ornamental design for a handle adapted for a stove or similar article, substantially as shown.

ALEXIS V. LAPTEFF.
